UNITED STATES PATENT OFFICE.

HENRY M. KNIGHT, OF LANCASTER, PENNSYLVANIA.

BORING-TOOL.

SPECIFICATION forming part of Letters Patent No. 356,138, dated January 18, 1887.

Application filed October 7, 1886. Serial No. 215,640. (No model.)

To all whom it may concern:

Be it known that I, HENRY M. KNIGHT, a citizen of the United States, residing at Lancaster, in the county of Lancaster, State of Pennsylvania, have invented certain Improvements in Boring-Tools, of which the following is a specification.

My invention relates to improvements in boring-tools for cutting out or enlarging openings already made; and it consists in the combination and arrangement of a number of parts, operating in the manner hereinafter described.

In the accompanying drawings, making part of this specification, Figure 1 is a plan view of my tool; Fig. 2, a longitudinal section of the same; and Fig. 3, a transverse section cut through line *v v*, Fig. 1.

Similar letters refer to similar parts throughout the several views.

The object of my invention is to construct a boring-tool having detachable blades or bits capable of such adjustment that the diameter of the tool may be readily increased or diminished.

This invention consists in a shank having a cutter-head, in slots in which the blades are carried, the shank and cutter-head having a bore, in which a bearing-rod with a conical end, on which the blades rest, is made adjustable.

The shank A, having a cutter-head, B, at one end, has a bore extending through said cutter-head and so much of the shank as may be necessary to afford room for the movement of the bearing-rod G and the action of its operating mechanism. The periphery of the shank, from the rear of the cutter-head to the stem R, has a screw-thread cut therein, upon which the set and jam nuts, hereinafter described, operate. The cutter-head has radial slots *b* cut therein, which carry the blades D. These blades rest upon the conical-shaped end *c* of the rod G, and have the edges upon which they rest of a shape to conform with the taper of the cone. The shank A has slots *a* cut through it into the bore from the cutter-head back the full length of the bore. Teats T on the rod G project through these slots,

and are engaged by set nuts N, which serve to regulate and hold the rod in position. The slots *b* are cut through the rear end of the cutter-head, so as to permit the inner ends of the blades to project somewhat beyond it, as shown at *d*. The jam-nut E serves to keep the blades in position when set, the inner end of the blades sloping outward from the cutting-edge to the base, as shown at *x*, Fig. 2, in order that the nut may hold it more securely.

As will be readily understood, the blades are set by loosening the jam-nut E and the set-nut N on the side of the teats T toward which the rod is to be moved. The other set-nut is then screwed up to force the rod into the position required, the movement of the rod back or forth regulating the distance the blades are to project and the diameter of the bore to be cut by them. Blades of different sizes can be used, as may be required by the work to be performed.

I wish it understood that I do not confine myself to any particular size or proportion or the kind of material used in the construction of my improved tool, for the same may be varied to suit the judgment of the mechanic making and using it, and the same general result be obtained.

Having thus described my improvement, what I claim as my invention, and desire to secure by Letters Patent, is—

1. The combination, with a tool having a screw-thread cut in the periphery of the shank thereof and a slotted cutter-head, and a bore extending through said shank and cutter-head, of adjustable blades, a rod having a cone-shaped bearing end, and teats projecting through slots in said shank and set-nuts, substantially as specified.

2. The combination, with a tool having a slotted cutter-head and a bore extending through the shank and cutter-head, of a rod having a cone-shaped bearing end and projections extending therefrom through slots in said shank, means for engaging said projections for the purpose of setting and holding said rod in position, and adjustable blades, substantially as specified.

3. The combination, with a tool having a slotted cutter-head and a bore extending through the shank and cutter-head, of a rod having a cone-shaped bearing end and projections extending therefrom through slots in said shank, means for engaging said projections for the purpose of setting and holding

said rod in position, adjustable blades, and jam-nuts for securing the same, substantially as specified.

HENRY M. KNIGHT.
